CLAIM

The ornamental design for a microphone, as shown and described.

DESCRIPTION

FIG. 1 is a front-side perspective view of a microphone; FIG. 2 is a rear-side perspective view of the microphone; FIG. 3 is a front elevational view of the microphone; FIG. 4 is a rear elevational view of the microphone; FIG. 5 is a top plan view of the microphone; FIG. 6 is a bottom plan view of the microphone; FIG. 7 is a right-side elevational view of the microphone; FIG. 8 is a left-side elevational view of the microphone; FIG. 9 is an enlarged front-side perspective view of a microphone portion of the microphone, shown separately to show aspects of the design that are not visible when combined; FIG. 10 is an enlarged rear-side perspective view thereof; FIG. 11 is an enlarged front elevational view thereof; FIG. 12 is an enlarged rear elevational view thereof; FIG. 13 is an enlarged top plan view thereof; FIG. 14 is an enlarged bottom plan view thereof; FIG. 15 is an enlarged right-side elevational view thereof; FIG. 16 is an enlarged left-side elevational view thereof; FIG. 17 is an enlarged front-side perspective view of a microphone stand portion of the microphone, shown separately to show aspects of the design that are not visible when combined; FIG. 18 is an enlarged rear-side perspective view thereof; FIG. 19 is an enlarged front elevational view thereof; FIG. 20 is an enlarged rear elevational view thereof; FIG. 21 is an enlarged top plan view thereof; FIG. 22 is an enlarged bottom plan view thereof; FIG. 23 is an enlarged right-side elevational view thereof; FIG. 24 is an enlarged left-side elevational view thereof; FIG. 25 is a cross-sectional view of the microphone stand portion of the microphone taken along line 25-25 of FIG. 19; FIG. 26 is an enlarged front-side perspective view of a microphone pop filter portion of the microphone, shown separately to show aspects of the design that are not visible when combined; FIG. 27 is an enlarged rear-side perspective view thereof; FIG. 28 is an enlarged front elevational view thereof; FIG. 29 is an enlarged rear elevational view thereof; FIG. 30 is an enlarged top plan view thereof; FIG. 31 is an enlarged bottom plan view thereof; FIG. 32 is an enlarged right side elevational view thereof; FIG. 33 is an enlarged left side elevational view thereof; and, FIG. 34 is an enlarged cross-sectional view of the microphone pop filter portion of the microphone taken in the direction of line 34-34 of FIG. 28. Portions of the microphone shown in broken lines form no part of the claimed design.
